UNITED STATES PATENT OFFICE.

JAMES WILSON, OF WATERTOWN, SOUTH DAKOTA.

INTERNAL GRINDER.

1,156,962.

Specification of Letters Patent.

Patented Oct. 19, 1915.

Application filed December 7, 1914. Serial No. 875,821.

To all whom it may concern:

Be it known that I, JAMES WILSON, a citizen of the United States, residing at Watertown, in the county of Codington and State 5 of South Dakota, have invented certain new and useful Improvements in Internal Grinders; and I do declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 This invention relates to improvements in what may be termed inside grinders.

The invention has for its object to provide facilities for effecting the ready adjustment of the grinding tool to the work in hand, especially in grinding interior annular 20 surfaces.

A further object is to provide for an oscillatory movement or pivoting of the mandrel-carrying member or holder for the requisite 25 application of the grinding tool in suitably reaching such inside or interior surfaces.

A still further object is to provide for the longitudinal or axial movement or adjustment of the grinding tool mandrel and to 30 provide for this manually.

A still further object is to provide for carrying out the aforesaid ends in a simple, expeditious and effective manner and with facility.

35 The invention therefore consists of certain instrumentalities and features of construction substantially as hereinafter fully disclosed and defined by the appended claims.

In the accompanying drawings is illustrated the preferred embodiment of my invention, wherein it will be understood that various changes and modifications may be made as to the detailed construction and arrangement of parts without departing from 40 the scope of the appended claims, and in which drawings

Figure 1 is a longitudinal sectional elevation, partly in side view, of my invention. Fig. 2 is an end elevation of the same. Fig. 50 3 is a transverse section taken on the line 3-3 of Fig. 1. Fig. 4 is a like section taken on the line 4-4 of the same figure.

In carrying out my invention I provide for suitably mounting a suitable support or bracket designated generally as 1, preferably 55 of the general structural outline as disclosed

particularly in Fig. 1, said bracket or support comprising a central frame-like member 2 with an open-ended tubular member 3 extending horizontally therethrough and 60 preferably integral therewith or otherwise fixed thereto, to receive and form a bearing for a mandrel 4 splined, feathered or slidable as at 5, thereon, a pulley 6 for transmitting motion to said shaft, a suitable belt 65 7 being applied to said pulley and driven from a suitable motor (not shown) as usual.

The bracket or support 2 has threaded into its lower end a screw-threaded terminal or stem 8, thus adapted for adjustable connection therewith to provide for the vertical 70 adjustment or raising and lowering of the bracket or support as conditions may call for in the use of the tool.

The stem or terminal 8 projects from a ball or spherical member 9, of which it is a part, said ball or spherical member being seated within a correspondingly formed socket 10 in the upper end of a post 11 suitably anchored in a base or 75 pedestal 12 suitably secured or bolted to the floor, as is obvious from Figs. 1 and 2. The anchoring of said post is preferably effected

by reducing the same diametrically as at 11^a the resultant reduced portion being passed through a passage 13 centrally in the 80 base 12, the shoulder formed by such reduction resting above the latter and upon a washer 15 preferably interposed between said shoulder and the top of said base, the lower end of said reduction 11^a having applied thereto a nut 16 firmly securing the 85 same in fixed relation to the base. These however it will be understood are matters of detail, which may be substituted by other

90 means having in view the same end, without any departure from the invention. The above described manner of mounting the support or bracket 2 upon the post 11 provides for imparting an oscillatory or approximate universal movement to said support for the sundry adjustments which may 95 be called for in applying the grinding tool to the surface to be operated upon.

The mandrel 4, which has a longitudinal slot or groove 17 therein to receive the spline or key 5 of the pulley 6 for providing for the slidable connection therebetween, carries at one end, beyond the tubular support or bearing 3, the grinding tool 18 which is controlled by the operator grasping a handle 100

19 outstanding from a frame-like member 20, with right-angled annular end portions 21,

105

110

one embracing the mandrel and confined between the grinding tool and a fixed collar 22 upon the mandrel, and the other annular end portion embracing and guided upon the tubular member or bearing 3, whereby, it is apparent that as the handle 19 may be manipulated by the operator, the grinding tool with the mandrel, may be moved longitudinally in suitably engaging the grinding tool with the object being operated upon, as is plain, the slideable or longitudinal movement of the mandrel being indicated by the dotted lines in Fig. 1.

The frame-like support or bracket 6 is suitably retained in operative position and adapted to yieldingly accommodate the varying action of the pulley-driving belt by means of a helical spring 23 under stress or extended in normal relation with said driving belt, the connection between said spring and said frame-like support being provided for preferably by a screw-eye 24 secured in the upper end of said support, said spring being suitably anchored to the floor as at 25 in any suitable way.

It is not thought that further or extended description is necessary to disclose the advantages and operation of my invention as the same are believed to be fully apparent from the foregoing.

I claim—

1. A device of the character described including a slideable tool mandrel, a driving

pulley thereon having a sliding connection therewith, a bracket for said mandrel, a base, a pivoted connection between said base and bracket and resilient means connected to said bracket to yieldingly retain the same in operative position.

2. A device of the type described, including a bracket or support, comprising a grinding tool equipped mandrel, a frame-like member having a tubular bearing extending from said frame-like member, said mandrel being equipped with a driving pulley having a sliding connection with said mandrel, and means for supporting said frame-like member, having adjustable connection therewith and a post, said adjustable connection having a ball and socket joint connection with said post.

3. A device of the character described, including a slideable tool mandrel, a driving pulley thereon having a sliding connection therewith, a bracket for said mandrel, a base, a ball and socket connection between said base and said bracket and resilient means connected to said bracket to yieldingly retain the same in operative position.

In testimony whereof, I affix my signature, in presence of two witnesses.

JAMES WILSON.
